CLAIM

the ornamental design for a retractable runner's cloth, as shown and described.

DESCRIPTION

FIG. 1 is a front view of a retractable runner's cloth, shown with the retractable clip in a retracted position;

FIG. 2 is a front view of the retractable runner's cloth in an alternate configuration, showing the retractable clip in a retracted position, with the back side of the clip turned upward;

FIG. 3 is a back view thereof;

FIG. 4 shows the retractable runner's cloth in an alternate configuration, with the retractable clip in a retracted position;

FIG. 5 is an alternate configuration of the retractable runner's cloth in a state of use, with the retractable clip in an unretracted position; and,

FIG. 6 is an alternate configuration of the retractable runner's cloth in a second state of use, with the retractable clip in an unretracted position.

The broken lines shown in FIGS. 1-2 depicts features on the top face of the clip of the retractable runner's cloth that forms no part of the claimed design. The broken lines shown in FIGS. 5-6 illustrate a hand that forms no part of the claimed design.

1 Claim, 6 Drawing Sheets
